REFRIGERATING APPARATUS

Robert S. Crane, Nashville, Tenn., assignor to
General Motors Corporation, Dayton, Ohio, a
corporation of Delaware

Application September 29, 1939, Serial No. 297,168

10 Claims. (Cl. 62—6)

This invention relates to refrigerating apparatus and more particularly to apparatus for either heating or cooling a gas by means of a refrigerating system.

One object of this invention is to provide an improved reverse cycle refrigerating system.

Another object of this invention is to provide an improved method of conditioning air.

Still another object of this invention is to provide improved controls for a reverse cycle refrigerating system.

A further object of this invention is to provide controls which prevent functioning of the refrigerating apparatus during the changeover from the one cycle to the other cycle.

Further objects and advantages of the present invention will be apparent from the following description, reference being had to the accompanying drawings, wherein a preferred form of the present invention is clearly shown.

In the drawings:

Fig. 1 is a diagrammatic view showing the refrigerating apparatus and the air circulating system; and

Fig. 2 is a diagrammatic view showing the electrical control circuits in combination with the pneumatic control system.

In order to simplify the disclosure of the air circulating ducts and the refrigerating system, the controls have been omitted in Fig. 1 and are shown separately in Fig. 2.

The air flow system

For purposes of illustration the air conditioning system has been shown in combination with a plurality of rooms 10 and 12. It is understood, however, that the system may be adapted for conditioning the air for a single enclosure or for a large number of enclosures. The air to be conditioned is circulated by means of a central blower system 14, which withdraws air from room 10 through the duct 16 and from the room 12 through the duct 18. Air flowing through the ducts 16 and 18 may be mixed with a varying amount of fresh air entering the duct system through the opening 20. The amount of fresh air introduced into the system is controlled by the bellows 24 in a manner to be described more fully hereinafter. The blower system 14 forces the air into the conditioning chamber 26 which is divided into a plurality of air flow passages 28, 30 and 32. In the main passage 28 there is provided a plurality of heat exchange sections 34, 36 and 38 which, for the purpose of illustration, have been shown as arranged in series. The

amount of air flowing through the passages 30 and 32 is controlled by the dampers 40 and 42 respectively. The passage 30 communicates with the duct 44 which conveys conditioned air to the room 10 whereas the passage 32 communicates with the duct 46 which conveys conditioned air to the room 12. The damper 40 which is similar in operation to the damper 42 is so constructed and arranged as to be able to completely close off the passage 30 whereby all of the air discharged into the room 10 will have circulated through the heat exchange coils 34, 36 and 38. The damper 40 is also capable of completely closing off the opening between the duct 44 and the passage 28 whereby all of the air supplied to the room 10 will have been by-passed around the heat exchange coils 34, 36 and 38. With this arrangement, it is possible to independently control the temperature in each of the rooms in a manner to be explained more fully hereinafter.

The reverse cycle refrigerating system

The refrigerating system comprises the compressor 48 which discharges compressed refrigerant through the line 50 to the oil separator 52, which may be of any conventional construction. A plurality of valves described hereinafter determine the direction of flow of the refrigerant during each cycle. During the cooling cycle, the compressed gas leaving the oil separator 52 passes through the pipes 54, 55 and 57 leading to the heat exchange coil 56. The heat exchanger 56 is arranged within the water tank 58 and functions as a condenser for the compressed refrigerant during the cooling cycle. The condensed refrigerant leaving the heat exchange coil 56 passes through the pipes 64 and 66 leading to the receiver 68. From the receiver 68 the liquid refrigerant flows through the pipe 70 which supplies liquid refrigerant to the heat exchange coils 34, 36 and 38 via branch pipes 72, 74 and 76. The pipes 72, 74 and 76 are each provided with the usual form of expansion valves 78, 80 and 82 respectively. During the cooling cycle the liquid refrigerant supplied to the heat exchangers 34, 36 and 38 is evaporated therein and returned to the compressor through the suction line 84 in which is placed a pressure regulating valve 86 of conventional construction and which performs its usual and well-known function. Water is supplied to the tank 58 by means of the water pump 60 driven by the electric motor 62. The water pump 60 may obtain its water from a deep well or any other convenient supply of water. In the event that water from the city water mains is

used, no pump is necessary. While the heat exchanger 56 has been shown as arranged within the water tank 58, it is apparent that certain features of the invention could well be used in combination with a refrigerating system employing an air cooled condenser. Oil separated from the compressed refrigerant in the oil separator 52 returns to the compressor through the oil line 88 leading to the compressor crankcase.

During the heating cycle the system is valved in the manner explained hereinafter so that the high pressure hot gas discharged from the compressor passes from the oil separator into the pipe line 90 which supplies the hot gaseous refrigerant to the heat exchangers 34 and 36 by way of pipe lines 92 and 94 respectively. The heat exchangers 34 and 36 serve to condense the refrigerant during the heating cycle and the condensed refrigerant returns to the liquid receiver 68 through by-pass lines 72a, 74a and the line 70. From the receiver 68 liquid refrigerant is caused to pass through the expansion valve 98 into the heat exchanger 56 which now functions as an evaporator for cooling the water circulated through the water tank 58. The gaseous refrigerant evaporated in the heat exchanger 56 returns to the compressor through the pipe line 57, valves 110 and 112, lines 100 and 84. A pressure relief valve 102 is provided in a by-pass 104 which permits refrigerant to be by-passed in the event that the refrigerant pressure becomes excessive.

The control system

The control valves which determine the direction of flow and consequently the cycle are all under control of a thermostatic unit generally designated by the reference character 114 and which is located in thermal exchange with the air in any one of the conditioned rooms most representative of the conditions in all of the air conditioned rooms. When the valves 106 and 110 are open and the valves 107, 108, 109, 116 and 118 are closed, the compressed gas is fed to the heat exchangers 34 and 36 arranged in the path of the cold air whereby heating of the air takes place. When the valves 106, 110 and 112 are closed and valves 107, 108, 109, 116 and 118 are open, then the compressed gas travels to the heat exchanger 56 where it is condensed and the liquid refrigerant thus condensed travels to the heat exchange coils 34, 36 and 38 where it is expanded by the warm air passing thereover as explained hereinabove. The solenoid valves 116, 118 and 120 are in the closed position during the heating cycle and are used for controlling the amount of cooling during the cooling cycle and are adapted to be controlled by the two-point thermostat generally designated by the reference character 122. The two-point thermostat is of the type in which the temperature responsive element 124, arranged in the path of the air leaving the heat exchangers 34, 36 and 38, actuates a bellows element 126 which operates the valves 128 and 130. The linkage mechanism between the bellows and the valves is so arranged that the one valve operates at a lower temperature than the other valve, for a purpose to be explained more fully hereinafter. When valve 128 is in its uppermost position, air from the bellows 274 is free to escape through the leak port 129. A similar leak port 131 is provided for the bellows 276.

As explained hereinabove the changeover thermostat 114 determines whether the apparatus is to heat the air or to cool the air. As shown in Fig. 2, the air pressure used for operating the

various bellows members is supplied by an air compressor 150 driven by an electric motor 152. The air compressed by the compressor 150 discharges into the usual form of compressed air reservoir 154 which communicates with the main air supply line 156 having one branch leading to the constant pressure valve 158 which is set to deliver air at a pressure of 13 lbs. and having another branch leading to the constant pressure valve 160 which is set to deliver air at a pressure of 17 lbs. For purposes of illustration, definite air pressure values and temperature values are referred to throughout the specification, but it is understood that these values are given for purposes of illustration only and that other values may be used by making the necessary adjustments. Air at 13 lbs. pressure is supplied to the chamber 162 provided within the pneumatically operated control valve generally designated by the reference character 164. Air at 17 lbs. pressure is likewise supplied to the chamber 166 in the same valve 164. The controls, as shown in Fig. 2, are set for producing heating and under these conditions air at 13 lbs. pressure is being supplied to the main air line 168 which is provided with a plurality of branches 169, 170, 172, 174, 176 and 178 which lead to the changeover thermostat 114, the pressure operated valve 180, the room thermostat 182, the room thermostat 184, the control 186 and the solenoid operated valve 188 respectively.

The refrigerating system is started by closing the manual switch 190 which energizes the fan motor 192 and thereafter closing the manual switch 194 which is in series with the water pump motor 62. It will be noted from Fig. 2 that the circuit arrangement is such that the water pump cannot be energized unless the air circulating fan 192 is energized since the manual switch 194 is in effect arranged in series with the manual switch 190. The compressor is under control of a first switch 196 forming a part of the pneumatic control element 186 which is responsive to the water temperature in tank 58 and a second switch 200 which is closed by the bellows 202 when the water pressure on the discharge side of the pump is sufficiently high for proper operation. In a typical installation, a water pressure of 25 lbs. has been found to be satisfactory.

In view of the above described arrangement, the compressor motor cannot be started until after the water pump motor has been started which, in turn, cannot be operated until after the main air circulating fan is in operation.

Upon closing the manual switch 190, a solenoid 204 is energized which controls an air valve 188. Energization of the solenoid 204 opens the valve so that air under pressure in the line 178 is free to flow into the line 206 leading to the damper operating bellows 24. The air pressure in the bellows 24 opens the outside air damper 22. Inasmuch as deenergization of the solenoid coil 204 causes the supply of air to the bellows 24 to be cut off, the outside air damper automatically closes when the air circulating mechanism 14 is stopped. Upon deenergization of the coil 204 the valve 188 closes whereby the air pressure in line 206 gradually drops as a result of leakage of air through the leak port 25. It is to be understood that the outside air damper 22 may be manually adjusted so as to admit the proper amount of air for any particular installation and for any particular condition which may exist. The solenoid valve 188, when open, also admits air to the air line 208 which supplies air to the

valve 210 which controls the supply of air to the bellows 212 and 214; the valves 216 and 218; and the humidity control unit 220. The valve 210 is provided with a leak port 211 for releasing the air from the main valve chamber. The humidity control unit 220 is so arranged that the humidity responsive element 222 projects into the return air duct adjacent the intake to the blower mechanism as shown in Fig. 1. The humidity responsive element 222 actuates the valve arm 224 which cooperates with the leak port 226 and the opening to the air line 228 in communication with the switch operating bellows 230. The arrangement is such that whenever air from the valve 210 is supplied to the humidity control element 220 and humidification is required, the valve arm closes the leak port 226 whereby air pressure is supplied to the bellows 230 to close the switch 232 arranged in series with the heating element 234. As shown in Fig. 1, the heating element 234 is disposed within a humidifier 236 adapted to contain a constant supply of water. Water for the humidifier is supplied through the line 238, and the level of water in the humidifier is controlled by a conventional fluid valve 240 which maintains the water level constant. In the event that the addition of moisture to the air is no longer required, the valve arm 224 moves to a position so as to cut off the supply of air under pressure to the switch operating bellows 230. As will be pointed out hereinafter, during the summer operating conditions, at which time the addition of moisture is not required, no air under pressure is supplied to the humidity control unit 220 whereby the circuit to the heating coil remains open.

When the control valve 210 is in the position shown, air under pressure is supplied to the pneumatically operated valves 216 and 218 whereby these valves are held open. As shown in Fig. 1, these valves are located in the by-pass lines 72a and 74a respectively whereby the refrigerant flowing from the heat exchangers 34 and 36 is free to flow around the expansion valves 78 and 80. Upon interruption of the supply of air under pressure to the valves 216 and 218, these valves automatically close.

As shown in Fig. 2, which illustrates the controls set for heating, air under pressure from the line 208, enters the bellows 212 so as to hold closed the switch 242 which is in circuit with the solenoid valves 106, 112 and 110. These valves are so constructed that, when current is supplied to the valves, the valves are held open. It will also be noted that the solenoid valve 110 is arranged in series with a switch 248 operated by the bellows 250. As shown in Fig. 1, the bellows 250 is responsive to the head pressure at the compressor outlet. In the event that the head pressure becomes excessive during the operation of the refrigerating system, the circuit through the valve 110 would be interrupted by the switch 248, whereby the valve 110 would automatically close the main suction line to the compressor. By virtue of the control arrangement shown in Fig. 2, the by-pass valve 112 is open at all times during the heating cycle; hence, when the main suction valve 110 is closed, all of the gas must travel to the compressor through the by-pass valve 112 arranged in the by-pass line 113. A hand valve 244 is arranged in series with valve 112 and is adjusted to permit the compressor to operate at a reduced head pressure as explained hereinafter. By virtue of the valve 10 and the by-pass line 113 a sufficient quantity

of gas is available at the compressor inlet even when the valve 110 is closed to prevent excessively low pressures at the compressor inlet and to prevent too frequent cycling of the compressor.

In referring to Fig. 2, it is apparent that during the heating cycle air from the valve 210 is also supplied to the bellows 214 which controls the switch 246. When air under pressure is supplied to the bellows 214 the switch 246 is held in the open position whereby the valves 107, 108 and 109 remain closed. However, when the supply of air to the bellows 214 is cut off the switch 246 closes the circuit to the solenoid valves 107, 108 and 109 whereby these valves are moved to the open position. As will be explained hereinafter, air flows through the valve 210 to the bellows 212 and 214 during the heating cycle only.

The room thermostats 182 and 184 are located in the rooms 10 and 12 respectively. These thermostats control the by-pass dampers 40 and 42 respectively which are arranged in the air ducts leading to the respective rooms in which the thermostats are located. These thermostats, as best shown in Fig. 2, have separate thermostatic strips 252 and 254 for the heating and the cooling cycles, the correct one being made effective by the air pressure change occasioned by the changeover thermostat 114. At a pressure of 13 lbs., the main operating bellows 256 of thermostat 182, for example, causes the needle valve 258 to remain in the position in which it is shown in Fig. 2. A pressure of 17 lbs., such as would be supplied to the bellows 256 during the cooling cycle, would cause the needle valve 258 to move to the right so as to place the supply of air to the damper operating bellows under the control of the thermostatic element 254 rather than under control of the thermostatic element 252. The thermostatic elements 252 and 254 control the supply of air to the damper operating bellows 260 in the conventional and well-known manner which needs no further description.

The purpose of the separate thermostatic elements 252 and 254 is to make the necessary adjustment for the seasonal change in temperature requirements as well as making the necessary adjustment for the change in the air pressure supplied to these control thermostats. The construction and arrangement of the thermostat 252 is such that less air is supplied to the damper operating bellows 260 during the winter season when it is desired to cause a greater amount of air for any one room to flow over the heat exchange coils 34 and 36. Likewise, the construction and operation of the thermostat 254 is such that during the cooling season less air is supplied to the damper operating bellows 260 at such times when a greater amount of cooling is required. The compressor motor is also under the control of the insertion thermostat 262 located near the discharge end of the water tank 58. This thermostat operates the bellows 264 which operates the valve arm 266 so as to close the supply of air to the bellows 268 which holds the switch 196 open in the event that the temperature within the water tank 58 becomes excessively low. It has been found desirable to stop the operation of the compressor when the temperature of the water in the tank 58 drops below 38° F. so as to prevent freezing of the water in the tank 58.

The two-point insertion thermostat 122 located in the conditioned air passage 28 controls the minimum temperature of the conditioned air when the system is functioning as a cooling system. The normally closed switches 270 and 272

are closed when air under pressure is supplied to the operating bellows 274 and 276 respectively. The closing of the switches 270 and 272 opens the valves 120, 116 and 118. The arrangement is such that a drop in temperature below the desired thermostatic setting operates first the one switch 272 and then the other switch 270, first cutting off the supply of refrigerant to the coil 34 by closing the valves 116 and 118 and thereafter closing the valve 120, cutting off the entire supply of refrigerant to all of the coils. During the heating cycle the two-point insertion thermostat is not supplied with air by virtue of the condition in the valve 180 whereby the switches 270 and 272 remain open and the solenoid valves 116, 118 and 120 remain closed during the heating season.

By virtue of the above described arrangement, it is apparent that each room is separately controlled by its own room thermostat, independent of the main changeover thermostat 114 which determines the cycles by varying the amount of air which is permitted to escape through the opening 117. As the temperature in the respective rooms rises during the heating cycle, the room thermostats begin to close off their respective dampers to the air leaving the heat exchange coils and allow a greater volume of air to bypass the coils. Thus, the condensing effect of the heat exchangers located in the air stream is decreased and the condensing pressure increases because of the lessening of the heating demand. Upon a continuation of this increase in condensing pressure the switch 248 controlling the valve 110 opens, thereby allowing the valve 110 to close the main suction line to the compressor. The decrease in the amount of gas available for compressor suction reduces the condensing pressure, whereby at a lower pressure the valve 110 is reopened. This action may occur frequently when the demand for heating is very nearly satisfied and will continue until the main thermostat 114 stops the operation of the system. The valve 112 arranged in the by-pass around the valve 110 operates simultaneously with the operation of valve 106 so that a sufficient amount of gas is available at the compressor inlet to prevent immediate pump-down to a vacuum and subsequent short-cycling at such times when the solenoid valve 110 is closed due to the high condensing pressure. The amount of gas passing through the valve 112 is controlled as explained hereinabove by operation of the hand valve 244 arranged in series with the valve 112.

The changeover thermostat 114 controls the changing over from heating to cooling and vice versa by varying the air pressure supplied to the pneumatically operated control valve 180. Preferably, the changeover thermostat is adjusted so as to cause a change of approximately 2 lbs. in the air pressure in line 115 per degree of temperature change. Thus, it may be said to start to act at a temperature of 72° F., and at 74° F. it has built up a pressure of 4 lbs. on the branch line leading to the control valve 180. This 4-lb. pressure, however, is insufficient to change the valve from the position in which it is shown in Fig. 2. Air at this same pressure is also supplied to the bellows 280 and the bellows 282. The bellows 280 operates the switch 284 which is arranged in series with the switch controlling the water pump. The bellows 280 is adapted to open the switch 284 when the pressure supplied to the bellows reaches the 8-lb. value. However, the bellows 282 which operates the switch 286 is adapted to close the switch 286 when the pres-

sure supplied to the bellows reaches a value of 12 lbs. By virtue of this arrangement, whenever pressures between 4 lbs., which corresponds to a temperature of approximately 74° F., and 12 lbs., which corresponds to a temperature of approximately 78° F., the water pump starter circuit is open resulting in an "off" cycle of the compressor and water pump. The values of 74° F. and 78° F. have been given for purposes of illustration, and it is presumed that between these temperatures neither heating nor cooling is required in any of the rooms.

As the temperature at the changeover thermostat 114 rises from 74° F. to 75° F. the resulting branch line air pressure supplied to the operating bellows 181 for the valve 180 operates the valve so that air under pressure of 13 lbs. supplied through the pipe 170 is also supplied through the pipe 171 leading to the bellows element 165 which operates the valve 164 so as to close off the air at 13 lbs. pressure and open the passage from the valve 160 which supplies air at 17 lbs. pressure to the main air line 168. This change in pressure supplied causes the valve 210 to cut off the supply of air from the line 208 to the bellows which operate the switches 242 and 246 and also renders inoperative the humidostat 220 so that during the cooling cycle no moisture is added to the air being conditioned. As a result of this change in pressure, the switch 242 assumes its normally open position, thereby cutting off the current to the solenoid operated valves 106, 110 and 112. Likewise, the normally closed switch 246 moves to closed position, thereby energizing the solenoid valves 107, 108 and 109 so as to open these valves. Upon valve 210 closing, the supply of air to the valves 216 and 218 is also cut off, thereby closing said valves so as to prevent the refrigerant from by-passing the expansion valves 78 and 80.

As pointed out hereinabove, the increase in the air pressure from 13 lbs. to 17 lbs. in the main air line 168 resets the room thermostats 182 and 184 so as to properly operate at the 17-lb. air pressure so as to maintain proper temperatures during the cooling cycle. The thermostat 124 arranged on the discharge side of the heat exchangers 34, 36 and 38 is also supplied with air from the valve 180 so as to supply the necessary air pressure for proper operation of the pneumatically operated switches 270 and 272. As pointed out hereinabove, these switches control the flow of refrigerant to the heat exchange coils 34, 36 and 38 which now function as evaporator coils.

It will be noted that, by virtue of the above described control system, all of the above valve operation, except that of the suction line control solenoid valve 110, occurs on air pressures from the changeover thermostat 114 between approximately 4 lbs. and 12 lbs., during which interval the water pump and compressor are inoperative; and regardless of whether the temperature is rising or falling, an air pressure of 8 lbs. in the branch line 115 leading from the changeover thermostat 114 will reset the valves which control the next cycle and do this during a period of "off" cycle for the water pump and compressor.

While the form of embodiment of the invention as herein disclosed, constitutes a preferred form, it is to be understood that other forms might be adopted, all coming within the scope of the claims which follow.

What is claimed is as follows:

1. In a reverse cycle refrigerating system, a first heat exchange means, a second heat exchange means, a compressor for withdrawing refrigerant vapor from one of said heat exchange means and discharging compressed refrigerant into the other of said heat exchange means, means for circulating a gas to be conditioned over said first heat exchange means, means for bypassing at least a portion of said gas around said first heat exchange means, means responsive to one function of the psychrometric condition of said gas for controlling said by-pass means, means for varying the capacity of said compressor, means for flowing a fluid over said second heat exchange means, means preventing the operation of said compressor when said fluid flowing means is ineffective, a changeover thermostat for changing over from the heating cycle to the cooling cycle, and means for preventing operation of the compressor during changeover from the heating cycle to the cooling cycle.
2. In a reverse cycle refrigerating system, a first heat exchange means, a second heat exchange means, a compressor for withdrawing refrigerant vapor from one of said heat exchange means and discharging compressed refrigerant into the other of said heat exchange means, means for circulating a gas to be conditioned over said first heat exchange means, means for bypassing at least a portion of said gas around said first heat exchange means, means responsive to one function of the psychrometric condition of said gas for controlling said by-pass means, means for varying the capacity of said compressor, means for flowing a fluid over said second heat exchange means, means preventing the operation of said compressor upon failure of said fluid flowing means, a changeover thermostat for changing over from the heating cycle to the cooling cycle, and means for preventing operation of the compressor during changeover from the heating cycle to the cooling cycle, said last named means comprising means for controlling the flow of fluid over said second heat exchange means.
3. In a reverse cycle refrigerating system, a compressor, first and second heat exchange units, refrigerant flow connections between said compressor and said first and second heat exchange units, said fluid-flow connections including a refrigerant line from one of said units to said compressor, a valve in said line, means responsive to high condensing pressure for closing said valve, means for bypassing said valve, and means for controlling the flow of refrigerant through said by-pass.
4. Air conditioning apparatus comprising, in combination, a compressor, complementary heat exchange units, fluid-flow connections between said compressor and said units, means for reversing the functions of said complementary heat exchange units, said fluid-flow connections including a refrigerant line from one of said units to said compressor, a valve in said line, means responsive to high condensing pressure for closing said valve, and means comprising a restricted by-pass for bypassing a small amount of refrigerant around said valve.
5. Air conditioning apparatus comprising, a reverse cycle refrigerating system, a compressor, a plurality of heat exchangers, refrigerant flow connections between said compressor and said heat exchangers, means for circulating a gas to be conditioned over one of said heat exchangers, 75 and means for bypassing at least a portion of said gas around said heat exchanger, means for varying the capacity of said compressor so as to compensate for changes in the load on said compressor, and means for rendering one portion of one of said heat exchangers ineffective during one cycle of operation.
6. In a reverse cycle refrigerating system for conditioning air for a plurality of enclosures, a compressor, a pair of complementary heat exchangers, refrigerant flow connections between said compressor and said heat exchangers, means for circulating air to be conditioned for said enclosure in thermal exchange with one of said heat exchangers, means for circulating an extraneous medium over the other of said heat exchangers, a separate duct for supplying conditioned air to each of said rooms, a separate bypass for bypassing air for each separate room around said one heat exchanger, means for reversing the heating and cooling functions of said heat exchangers, and means for reducing the capacity of said compressor so as to compensate for changes in the load on said compressor.
7. In combination, a reverse cycle refrigerating system comprising a compressor and a plurality of heat exchange coils arranged in refrigerant flow relationship, means for flowing air for a plurality of rooms in thermal exchange relationship with one of said coils, means for bypassing air for said rooms around said one coil, independent means for varying the effective surface of said one coil, and means for unloading said compressor when the load on said compressor exceeds a predetermined value such as results when a major portion of the air bypasses said one coil.
8. In combination, a first heat exchange means, a second heat exchange means, a compressor for withdrawing refrigerant from one of said heat exchange means and discharging compressed refrigerant into the other of said heat exchange means, means for circulating a gas to be conditioned over said first heat exchange means, means to circulate a fluid over said second heat exchange means, control means for operating said refrigerating system so as to heat said gas throughout a predetermined low temperature range and for operating said refrigerating system to cool said gas throughout a predetermined high temperature range, said control means including means for automatically increasing the effective heat transfer surface of one of said heat exchange means in response to changing over from heating to cooling.
9. Air conditioning apparatus comprising in combination, a pair of complementary heat exchange units, a refrigerant compressor withdrawing refrigerant vapor from one of said units and discharging compressed refrigerant vapor into the other of said units whereby one of said units serves as an evaporator and the other of said units serves as a condenser, means for reversing the functions of said complementary heat exchange units, one of said units comprising a plurality of sections, means for preventing the flow of refrigerant through one of said sections when heating of the air is required, and means for bypassing air around said sections in response to changes in the requirements for conditioned air.
10. In combination, an air conditioning chamber, means for circulating air to be conditioned through said chamber, means for cooling the air flowing through said chamber, means for dis-

charging the air leaving said chamber into a plurality of rooms to be conditioned, means for introducing fresh air into said chamber, means for controlling the introduction of fresh air to said chamber, means for returning air from each of said rooms to said chamber, means for by-passing a variable amount of air for one of said rooms

around said air cooling means in response to changes in the temperature within said one room, and means responsive to the temperature in another of said rooms for controlling said air cooling means.

ROBERT S. CRANE.
